(57) **CLAIM**

The ornamental design for a hanger with clip for a gutter guard assembly, as shown and described.

DESCRIPTION

FIG. 1 is a perspective view of a hanger with clip for a gutter guard assembly;

FIG. 2 is another perspective view of the hanger of FIG. 1; FIG. 3 is a rear elevation view of the hanger of FIG. 1; FIG. 4 is a front elevation view of the hanger of FIG. 1; FIG. 5 is a right-side elevation view of the hanger of FIG. 1;

FIG. 6 is a left-side elevation view of the hanger of FIG. 1; FIG. 7 is a top plan view of the hanger of FIG. 1; and, FIG. 8 is a bottom plan view of the hanger of FIG. 1. The broken lines shown in the drawings illustrate portions of the hanger that form no part of the claimed design.
